ABSTRACT

Apparatus for the conversion of a solid material to a gaseous phase by sublimation in which the rate of vaporisation of the solid material is controlled in accordance with the pressure of the gas formed by the conversion. The apparatus finds particular application in the continuous, automatically controlled sublimation of uranium hexafluoride prior to its conversion to uranium dioxide in a gas phase reaction with steam and hydrogen.

CROSS-REFERENCES TO RELATED APPLICATIONS

This application is a division of application Ser. No. 132,649 in the names of Gillies et al filed Apr. 9, 1971.

BACKGROUND OF THE INVENTION

This invention relates to apparatus for the solid to gaseous conversion of a material which sublimes.

SUMMARY OF THE INVENTION

According to the invention apparatus for the solid to gaseous conversion of a material which on heating sublimes from the solid phase to the gaseous phase comprises a container for the solid material, the container having a gas outlet, and means for spraying hot water over the container to cause vaporisation of the material in the container, the rate of supply of hot water to the container and therefore the rate of vaporisation of the material being controlled in accordance with the pressure of gas in the container.

In a preferred form of the invention the hot water spray is derived by the recirculation of water gathered at the base of the container after spraying over the container, recirculation of the water being by a steam ejector which reheats the water, the supply of steam to the ejector and hence the rate of recirculation of the water being controlled in accordance with the pressure of gas in the container.

A typical industrial process with which the apparatus of the invention may be concerned is the continuous conversion of uranium hexafluoride into uranium dioxide by reaction with steam and hydrogen in a gaseous phase reaction, as described in the specification of our copending application referred to above. In such a process a continuous automatically controlled supply of gaseous phase uranium hexafluoride is required. Normally uranium hexafluoride is supplied for such processes in the solid state in transport containers.

DESCRIPTION OF THE DRAWING

An apparatus according to the invention will now be described by way of example with reference to the accompanying drawing which shows a sectional view of such apparatus.

DESCRIPTION OF THE PREFERRED EMBODIMENT

Referring to the drawing a vertically orientated tank 1 is shown having a removable lid 2. Located in the tank 1 is a cylindrical transport container 3 containing solid phase uranium hexafluoride. Location for the container 3 in the tank 1 is provided by an annular upstand 4 fitted in the base of the tank 1 and by locking bars 5 pivotably attached to the walls of the tank 1 immediately below the lid 2 and bearing on the top of the container 3. The top of the container 3 is provided with a lifting attachment 6 and a filler/outlet valve 7. The valve 7 is connected into a line 8 for supply of gaseous phase uranium hexafluoride to a rotary kiln. Located immediately above the container 3 are two annular pipes 9 and 10, the internal diameters of which allow the container 3 to be loaded into or removed from the tank 1 without difficulty. Both of the annular pipes 9

and 10 have equidistantly spaced apertures in their inner surfaces which allow water supplied in the pipes to be sprayed onto the top of the container 3. The upper annular pipe 9 is connected to a cold water supply line 11 whilst the lower annular pipe 10 is connected into a hot water supply line 12 which extends down towards the base of the tank 1 where it connects into a steam ejector 13. A pipe 14 connects the ejector 13 into the bottom of the tank 1. A line 15 supplies steam to the ejector 13. The supply of steam to the ejector 13 is controlled by means of an air controlled valve located in the line 15 which is actuated by an air signal from a pressure transducer located in the line 8. Thus the steam supply to the ejector 13 is controlled by the pressure of gaseous phase uranium hexafluoride in the line 8. When the valve 7 is in the open position the pressure of gaseous phase uranium hexafluoride in the line 8 will be the same as in the cylinder 3.

In operation a container 3 containing uranium hexafluoride in the solid phase is loaded into the tank 1 and located in position by means of the upstand 4 and the locking bars 5. The line 8 is then connected to the valve 7 which is then opened. Steam is supplied by the line 15 to the ejector 13 causing it to draw water 16 from the base of the tank 1 via the pipe 14 and pass it mixed with steam up the line 12 into the annular pipe 10 from which it emerges as a hot water spray which is directed onto the top of the container 3. The water from the hot spray runs down the outside of the container 3 and collects in the base of the tank 1 where it is available for recirculation by the ejector 13. The hot water spray heats the walls of the container 3 and converts the solid phase uranium hexafluoride contained therein into the gaseous phase which passes out of the cylinder 3 via the valve 7 into the line 8.

The pressure of the gaseous uranium hexafluoride controls the amount of steam supplied to the ejector 13 and hence controls the volume of hot water sprayed on to the top of the container 3 from the annular pipe 10. In this way the heat supply to the container 3 and thus the rate of conversion of the uranium hexafluoride from the solid to the gaseous phase is automatically controlled.

The cold water spray from the annular pipe 9 is used to cool down the container 3 when it is required to stop the conversion of uranium hexafluoride from the solid to the gaseous phase.

We claim:

1. Apparatus for the solid to gaseous conversion of a solid material which on heating sublimes from the solid phase to the gaseous phase, comprising, in combination, a container in the form of a pressure vessel containing a solid sublimable material, said container having a gas outlet in the upper portion thereof, means for spraying hot water over the container to cause vaporization of the material in the container, and means for controlling the rate of supply of hot water to the container and therefore the rate of vaporization of the material in accordance with the pressure of gas in the container.

2. Apparatus as claimed in claim 1 further comprising means for collecting water at the base of said container after spraying over the container, said means for spraying including means for recirculating said collected water and spraying it over the container, said recirculation, means including a steam ejector which recirculates and reheats the water, and said control

means comprising means responsive to gas pressure in the container for automatically controlling the supply of steam to said ejector in accordance with said gas pressure.

3. Apparatus as claimed in claim 1 wherein said solid material is solid phase uranium hexafluoride.

4. Apparatus as claimed in claim 3 wherein said container is a transport container removably mounted in a tank for collecting water at the base of said container

after spraying over the container, said spraying means including means for recirculating said collected water and spraying it over the container, said recirculating means including a steam ejector which recirculates and reheats the water, and said control means comprising means responsive to gas pressure in the container for automatically controlling the supply of steam to said ejector in accordance with said gas pressure.
